(57) **CLAIM**

I claim the ornamental design for the fastening clip, as shown and described.

DESCRIPTION

FIG. 1 Is a backside perspective of an assembled fastening clip showing my new design.

FIG. 2 Is a frontside perspective of an assembled fastening clip.

FIG. 3 Is a sideview of an assembled fastening clip. Opposite side elevation is a mirror image of this view.

FIG. 4 Is a backside perspective view of a disassembled fastening clip; and,

FIG. 5 Is a frontside perspective view of a disassembled fastening clip.
